UNITED STATES PATENT OFFICE.

PARVIN WRIGHT, OF VANCOUVER, BRITISH COLUMBIA, CANADA.

MAGNETIC SEPARATOR.

1,177,981.

Specification of Letters Patent.

Patented Apr. 4, 1916.

Application filed May 14, 1914. Serial No. 838,504.

To all whom it may concern:

Be it known that I, PARVIN WRIGHT, a citizen of the United States, residing at Vancouver, in the county of Vancouver, Province of British Columbia, and Dominion of Canada, have invented a new and useful Magnetic Separator, of which the following is a specification.

This invention relates to apparatus for separating magnetic material from sand, gravel, etc., and is an improvement on my application for United States Patent, Serial Number 769,895, filed May 26th, 1913.

The object in general of the invention is to provide apparatus of this character which will be highly efficient in operation and simple in construction.

Other objects will appear from the following description.

Referring to the drawing: Figure 1 is a plan view of the apparatus. Fig. 2 is a longitudinal section thereof, taken on line x^2-x^2 , of Fig. 1. Fig. 3 is a diagrammatic view of the circuits controlling the electro-magnetic material separating element of the apparatus and the switch for said circuits. Fig. 4 is a developed view of a part of the switch for the circuits of the magnetic separating element.

The apparatus is mounted upon a frame 1. In the upper part of said frame is mounted an inclined flume 2 for receiving the material. The flume 2 is formed with a plurality of longitudinal channels 3 in which the material flows. The bottom of each channel 3 is provided with a slot 4 which receives a bar 5, the forward end of which is pivoted to the flume at 6. A shaft 10 is journaled in the frame 1 under the flume 2 at the rear ends of the slots 4, upon which shaft is mounted a plurality of rollers 11 which respectively project into the rear ends of the respective slots 4. The rear end of each of the bars 5 is forked at 12 to receive a cam

on shaft 10, by means of which cams the bars 5 are moved up and down on their pivots to agitate the material in the flume so that the fine sand will drop through the lower rear ends of the slots 4. The slots 4, bars 5, and rollers 11 form a screen for screening the material before it leaves the flume. Located below the flume 2, and directly under the slots 5 therein, is a chute 18 upon which the fine sand drops from the flume 2 through said slots. Mounted on a shaft 19, journaled in the frame 1 under

the chute 18, is a magnetic drum 20. The lower end of the chute curves downwardly part way around the drum 20. A curved chute 21 also curves part way around the drum from the lower end of the chute 18, and the upper end of the chute 21 rests slightly away from the lower end of chute 18, forming a space therebetween through which the sand drops from the chute 18 onto the chute 21. A curved plate 25 is located along the outside of chute 21, forming a channel 26 therebetween into which the surplus water flows from the chute 18. Within the drum 20 are located a plurality of electro-magnets 30, arranged in groups *a*, *b*, *c* and *d* and connected through a wiring system 31 to a generator 32. A copper casing 20' incloses the magnets 30 in the drum and forms the periphery of the drum.

The energization of the magnets 30 is controlled by a switch 33. The switch 33 comprises a drum 35 mounted on the shaft 19, having a pair of circular contact rings 36 and 36' wiped by brushes 37 connected to the generator 32 by wires 38, and a plurality of contact members 39, 40 and 41, connected to the respective groups *a*, *b*, *c* and *d* of the magnets 30 by wiring 31. A brush 45 is adapted to wipe the contacts 36 and 39, a brush 46 is adapted to wipe contacts 39 and 40, a brush 47 is adapted to wipe contacts 40 and 41, and a brush 48 is adapted to wipe contacts 41 and 36'. The contacts 36, 39, 40, 41 and 36' are of such formation and so timed that said brushes will wipe them only at such times as to short out said magnets when they reach the highest point of the drum 20 and until they reach the lowest point thereof while the drum travels in the direction of the arrow 42. To make this more clear: When the series of magnets *a* are at the left of a vertical line drawn through the center of the drum 20, and the series of magnets *d* approach the highest point of the drum, the brushes 45 wipe the contacts 36 and 39, and the brushes 48 wipe the contacts 41 and 36' and short out said magnets. When the series of magnets *d* are at the left of a vertical line drawn through the center of the drum 20, and the series of magnets *c* approach the highest point of the drum, the brushes 45 and 46 wipe the contacts 36 and 39, and 39 and 40, respectively, and short out said magnets. When the series of magnets *c* are at the left of a vertical line through the center

of the drum, and the series *b* approach the highest point thereof, the brushes 46 and 47 wipe the contacts 39 and 40, and the contacts 40 and 41, respectively, and short out said magnets. When the series of magnets *b* are at the left of a vertical line through the center of the drum, and the series *a* of said magnets approach the highest point of said drum, the brushes 47 wipe the contacts 40 and 41, and the brush 48 wipes the contacts 41 and 36' and short out said magnets. The energization of the magnets is then repeated in the above described order, which constantly keeps the periphery of the drum 15 to the right of a vertical line through the center of the drum energized, so that the magnetic materials are attracted to the drum and carried to the highest point thereof, and the periphery of the drum to the left of 20 said line deenergized. As the current passes through said magnets, their heads 50 are energized, which attracts the magnetic material against the drum casing 20', so that said material is conveyed by the rotation of 25 the drum from the lower end of chute 21 to the highest point of the drum, where the material is delivered to a brush 51 mounted upon shaft 51', which brush strips the magnetic material from the drum and delivers 30 it into a launder 52. From the launder the magnetic material is delivered into a classifier 55. The classifier 55 comprises a pair of vertical parallel pipes 56 and 57 which communicate with each other at 60. The lower end of pipe 57 communicates with a pipe 61, which communicates at one end with a water tank 65, and is connected at its other end by a flexible elbow 61' with an outlet 66. The upper end of pipe 57 communicates with a trough 67. A pipe 68 leads from the tank and supplies water between the drum 20 and brush 51 to assist the brush in removing the material from the drum. A flume 70 is located below the drum 20 upon which the 40 non-magnetic material is delivered from chute 21 and the surplus water is delivered from the channel 26. Said flume is provided with mercury trays 71, holding mercury and riffles 72, which collect and hold the gold, 45 platinum, and heavy metals, while the sand is washed over the lower end of the flume. A water wheel 75, mounted on shaft 76 journaled in the frame 1, is located below the lower end of the flume 2, which receives the gravel, coarse sand, and excess water from the lower end of the flume and is rotated thereby. A splash board 77 receives the gravel, coarse sand, and water from the wheel 75 and protects the riffles 72 therefrom.

The object of the water wheel is to furnish the power to run the machine. The magnetic drum 20 is driven by said wheel through the medium of pinion 80 on wheel shaft 76, pinion 81 on stud 82 on the frame.

1, which pinion meshes with pinion 80, pulley 83 rotatable with pinion 81, pulley 84 on drum shaft 19 and belt 85 which travels over said pulleys. From the drum the power from the water wheel 75 is transmitted to the brush 51 to rotate the brush, through the medium of pulley 86 on drum shaft 19, pulley 87 on the brush shaft 51', and belt 89 which passes over said pulleys. Power from the wheel 75 is also transmitted to the shaft 10 to rotate said shaft, through the medium of pulley 90 on drum shaft 19, pulley 91 on shaft 10, and belt 92 which passes over said pulleys. Although I have herein shown the apparatus as driven by the water wheel 75, other power may be employed if desired.

The operation is as follows: The material to be separated is first placed upon the upper end of the flume 2 and washed down the flume by water supplied thereto in any desirable manner. As the material passes over the bars 5 and is agitated by the movement of said bars caused by cams 15 and by the rollers 11, the fine sand and associated metals drop through the lower ends of the slots 4 onto the chute 18 and run down said chute and off the lower end thereof, while the surplus water flows in the channel 26 and onto the flume 70. As the sand and associated metals run off said chute, the non-magnetic material runs down the chute 21 onto the flume 70, while the magnetic material is attracted to the lower portion of the periphery of the drum 20 by the magnetism of the magnets 30 and carried around with the drum to the brush 51 which strips the magnetic material from the drum and delivers it into the launder 52. From the launder the magnetic material flows into the pipe 56 and then into the pipe 57 of the classifier 55, where it meets an upflow of water flowing from the tank 65 through pipe 61. The force of the water is such that it carries the lightest material, for example, magnetite, upward and delivers it into the trough 67, while the heavier material, for example, ferro nickel, sinks through the upflow and passes out through the outlet 66 to any suitable receptacle (not shown). The force of the upflow may be varied in any suitable way, as, for example, by bending the flexible elbow 61' and tilting the outlet pipe 66. The non-magnetic material when delivered onto the flume 70 is washed down said flume by the water from the channel 26, over the mercury trays 71 and riffles 72, which collect and hold the gold, platinum, and heavy metals while the sand is washed off the lower end of the flume.

What I claim is:

1. In a magnetic ore separator, a flume into which the ore is first placed and washed down, means for discharging the fine sand from said flume, means for separating the

- fine sand from the surplus water therein, a magnetic separating device for collecting the magnetic material from said fine sand when said surplus water is separated therefrom, means for discharging said magnetic material from said separating device, a second flume, means for delivering the non-magnetic material upon said second flume, and means for delivering said surplus water to said second flume to wash the non-magnetic material down said flume.
2. In a magnetic ore separator, a flume into which the ore is first placed and washed down, means for discharging the fine sand from said flume, a magnetic separating device, said separating device being adapted to collect the magnetic materials from said fine sand, a flume into which the non-magnetic material is delivered, means for washing the non-magnetic material down said flume, mercury trays and riffles in said flume for collecting the non-magnetic metals, a power wheel operated by the excess water and ore residue flowing from said first flume, said power wheel being adapted to drive said separating device, and a splash board covering said riffles upon which the water and ore residue is delivered from said power wheel.
3. In an ore separator, a rotatably mounted magnetic separating device comprising magnets, a chute for receiving finely divided ore together with water at a point adjacent to said magnetic separating device, a chute extending adjacent to the delivering end of the aforesaid chute, and spaced therefrom to permit finely divided ore to pass between said chutes and from the first chute onto the second named chute, said second named chute being located within the field of influence of the magnetic separating device, and a plate extending adjacent to said second
- named chute and spaced therefrom to form a channel between said plate and said second named chute for receiving water from said first named chute.
4. In an ore separator, a magnetic separating device comprising a rotatably mounted drum provided with magnets, a chute extending over said drum and partly around the same for delivering finely divided ore together with water at a point adjacent to said drum, a chute extending partly around the lower portion of said drum and having its upper end adjacent to the lower end of the first named chute and spaced outwardly therefrom to permit finely divided ore to pass from said first named chute onto said second named chute and to be guided by said second named chute in proximity to the drum, said second named chute being located in the field of influence of the magnetic separating device sufficiently close to the lower edge of said first named chute to permit excess water to pass to the outside of said second named chute.
5. In an ore separator a rotary magnetic separating device, a chute extending partly around the lower portion of the device and being within the field of magnetic influence thereof, a second chute spaced outwardly from the first chute and being substantially concentric therewith, and means to deliver finely divided ore together with water upon the upper end of the first chute, said second chute adapted to receive the water from said means.

In testimony whereof, I have hereunto set my hand at Vancouver, B. C., this 30th day of April, 1914.

PARVIN WRIGHT.
